UNITED STATES PATENT OFFICE.

WILLIAM DAVID HUGHES, OF CONDON, OREGON.

FLY-PAPER HOLDER.

1,318,562.

Specification of Letters Patent. Patented Oct. 14, 1919.

Application filed November 12, 1918. Serial No. 262,158.

To all whom it may concern:

Be it known that I, WILLIAM D. HUGHES, a citizen of the United States, residing at Condon, in the county of Gilliam and State of Oregon, have invented certain new and useful Improvements in Fly-Paper Holders, of which the following is a specification.

The invention provides means for catching winged insects, such as flies, mosquitos, gnats and the like so as to rid rooms and other places of abode of such annoying pests.

For catching flies and other winged insects, paper or other suitable sheet material is provided having one side coated with an adhesive, such as liquid glue, whereby an insect alighting thereon is entangled and prevented from escaping.

The present invention provides novel means for holding the glue covered or entangling sheet in proper and exposed position for ensnaring and catching flies and other winged insects.

The drawing illustrates a preferred embodiment of the invention; however, it is to be understood that in adapting the same to meet different conditions, various changes in the form, proportion, and minor details of construction may be resorted to without departing from the nature of the invention as claimed hereinafter.

Referring to the accompanying drawing,

Figure 1 is a perspective view of a holder for a sheet of fly paper embodying the invention.

Fig. 2 is a top view thereof.

Corresponding and like parts are referred to in the following description and indicated in both views of the drawing by like reference characters.

The holder comprises a board which may be of any material construction or size. This board is adapted to be suspended in any manner so as to expose both sides and thereby admit of a sheet of fly paper being applied to each side thereof. As indicated most clearly in Fig. 1 an opening 2 is provided at the upper end of the board 1 to receive a suspending strand such as a cord, thereby admitting of the board assuming various positions according to the direction of air currents.

Cleats or strips 3 are applied to opposite vertical edge portions of the board or frame 1 and are rabbeded on their inner faces adjacent their inner vertical edges, as indicated

at 4, to provide spaces for receiving the vertical edge portions of the sheet 5 of fly paper. It is to be understood that a sheet of fly paper 5 is adapted to be held in position on each side of the board or frame 1, whereby the capacity of the device for catching flies and like insects is twofold. The strips or cleats 3 may be of any material and may be attached to the vertical edge portions of the board or frame 1 in any manner. The strips 3 serve as reinforcing means for bracing the vertical edge portions of the board 1, thereby admitting of such board consisting of comparatively thin material such as veneer, paste board, or the like. The fastening means 6 employed for securing the strips or cleats 3 may pass through the material comprising the board, or frame 1 and through the outer thickened edge portions of the strips applied to opposite sides of the board, thereby securing the several parts together.

Ordinary fly paper is coated upon one side with a glue preparation which provides a sticky surface for the entanglement of insects alighting thereon and there is a tendency for such preparation to drip particularly when the fly paper is arranged in vertical position. To catch the drippings, a trough or tray 17 is provided and is secured to the lower portion of the board or frame 1. The trough 7 as disclosed is of V form and is closed at its ends by triangular-shaped pieces through which fastenings 8 pass to retain the trough in position.

In practice a holder constructed substantially as set forth herein has a sheet of fly paper applied to each side and retained in place by means of the rabbed strips or cleats, the holder being suspended in any manner. The construction is such as to admit of the sheet being easily placed in position and easily changed when desired so that a sheet of fly paper when rendered unsuitable for further effective service may be quickly replaced by a new sheet, the drippings collecting in the trough 7 may be readily removed therefrom as occasion may require.

The foregoing description and the drawing has reference to what may be considered, the preferred, or approved, form of my invention. It is to be understood that I may make such changes in construction and arrangement and combination of parts, materials, dimensions, *et cetera*, as may prove

expedient and fall within the scope of the appended claim.

It is noted that the invention may be utilized as means for receiving the usual poison paper which is placed in dishes containing water and disposed upon tables and other suitable supporting means. The poison paper may be placed in position and its lower edge allowed to dip into water contained in the trough 7. By suspending the holder it is out of the reach of children and domestic pets.

Having thus fully described my invention, what I claim as new and desire to secure 15 by Letters Patent is:—

A device of the character specified, com-

prising a board, rabbeted strips at the vertical edges of both sides of the board, a trough closed at its ends and projecting beyond opposite sides of the board with its closed ends embracing the edges of the lower end of the board and fastenings passing through the closed ends of the trough and entering the edge portions of the board and pivotally connecting the trough to the board.

In testimony whereof I affix my signature in presence of two witnesses.

WILLIAM DAVID HUGHES.
